US00D982815S

(12) **United States Design Patent** (10) **Patent No.:** **US D982,815 S**
(45) **Date of Patent:** **** Apr. 4, 2023**

(54) **PROJECTOR LIGHT**

(71) Applicants: **Tiehua Tan**, Hunan (CN); **Bin Liao**, Guangdong (CN)

(72) Inventors: **Tiehua Tan**, Hunan (CN); **Bin Liao**, Guangdong (CN)

(**) Term: **15 Years**

(21) Appl. No.: **29/773,287**

(22) Filed: **Mar. 9, 2021**

(51) **LOC (14) Cl.** **26-05**

(52) **U.S. Cl.**

USPC **D26/106**; D26/93

(57) **CLAIM**

The ornamental design for a projector light, as shown and described.

DESCRIPTION

FIG. 1 is a front perspective view of a projector light showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the projector light that form no part of the claimed design.

1 Claim, 8 Drawing Sheets
